UNITED STATES PATENT OFFICE

164,507

LIGHT FIXTURE

Clyde D. McCann, Des Moines, Iowa

Application November 10, 1947, Serial No. 142,423

Term of patent 14 years

(Cl. D48—4)

To all whom it may concern:

Be it known that I, Clyde D. McCann, a citizen of the United States, residing at Des Moines, in the county of Polk and State of Iowa, have invented a new, original, and ornamental Design for Light Fixture, of which the following is a specification, reference being had to the accompanying drawing, forming a part thereof.

Fig. 1 is a perspective view, Fig. 2 is a front view, and Fig. 3 is a top view of a light fixture, showing my new design.

I claim:

The ornamental design for a light fixture, substantially as shown.

CLYDE D. McCANN.
